Primary Examiner — Cathron C Brooks*Assistant Examiner* — W. A. Teddy Falloway(74) *Attorney, Agent, or Firm* — Andrew R. Aranda(57) **CLAIM**

The ornamental design for a package having two pouches, as shown and described.

DESCRIPTION

FIG. 1 is a top and right side perspective view of a package having two pouches;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines shown in FIGS. 1-6 illustrate portions of the package having two pouches, and form no part of the claimed design.
